UNITED STATES PATENT OFFICE.

GEORGE O. S. CONWAY, OF STONEFIELD, ASSIGNOR OF ONE-HALF TO JAMES COOPER AND FREDERICK FAIRMAN, BOTH OF MONTREAL, CANADA.

CAR-COUPLING.

SPECIFICATION forming part of Letters Patent No. 257,659, dated May 9, 1882.

Application filed November 28, 1881. (No model.)

To all whom it may concern:

Be it known that I, GEORGE O. S. CONWAY, of Stonefield, in the county of Argenteuil and Province of Quebec, Canada, have invented 5 certain new and useful Improvements in Car-Couplers; and I do hereby declare that the following is a full, clear, and exact description of the same.

My invention has reference to that class of 10 automatic car-couplers which are so constructed that cars provided with them can be coupled to others having the ordinary link-and-pin arrangement, and may be thus described: The draw-head in outward appearance resembles 15 those of ordinary construction; but instead of the usual rectangular chamber following the outline of the outside, the chamber formed in the draw-head in my invention is oval in section, and has formed in its front the opening 20 to receive the link, the mouth being flared from this in every direction and the chamber flared on the line of the link from its rear end. Within this chamber is contained a ball of cast metal somewhat less in diameter than the internal 25 width of the link. This may be cast loose in the chamber, or the draw-head so constructed that it may be inserted. The normal position or seat of this ball in the chamber is just below and in rear of the opening through which 30 the link enters, in which place it will lie within the link and retain it in position when the cars are coupled. To lift this ball and allow the link to be drawn out when the cars are to be 35 uncoupled I adopt the following device: I place in a slot formed in the under side of the draw-head an arm mounted rigidly on a pivot pin or spindle, which passes through the draw-head and is carried out at one side. By turning 40 this pivot and raising the arm, for which suitable means are provided, the ball is thrown up into an inner recess formed in the rear and upper part of the chamber, and the link so released therefrom may be drawn out. For full 45 comprehension, however, of the invention, reference must be had to the annexed drawings, in which—

Figure 1 is a longitudinal vertical sectional elevation of my invention; Fig. 2, a top view, partly broken away; Fig. 3, a bottom view, 50 looking up; Fig. 4, a side view; and Fig. 5, a

transverse vertical sectional elevation on line *x x*, Fig. 1.

Similar letters of reference indicate like parts.

A is the draw-head, *A'* being the internal chamber of the section shown in Figs. 1, 2, 55 and 5, and *A*² the mouth through which the link *B* enters. This mouth *A*² is, as shown in Figs. 1 and 2, made flaring, so that the link can be introduced at almost any angle, thus allowing cars of different heights to be coupled together. The flaring outline of the back of the chamber *A'*, on the plane in which the link lies, also facilitates its entry.

C is a ball, of cast metal, which, when the link *B* has been introduced into the chamber 65 *A'* and the cars coupled together, lies in the position shown in Fig. 1, within the link, and keeps it in place.

*A*³ is a slot formed in the under side of *A*, and *D* a pivot pin or spindle passing through 70 the draw-head and on either or both sides beyond it, and *E* is an arm, the upper surface of which may correspond with the outline of the chamber *A'* at that point. This is mounted rigidly on the spindle *D*, and when not in use 75 is generally allowed to hang down, as shown in Fig. 1, thus leaving the slot *A*³ open and allowing any dirt to fall through it.

D' is a crank mounted on the spindle *D*, from which a cord or rod may be taken to the 80 top of the car for raising said crank and turning the spindle *D*.

F is a rod terminating in a fork, *F'*, with slotted sides pivoted to the end of *D*, so as to form a universal joint therewith, and furnished at its outer end with a suitable handle or ring. This rod is of length sufficient to project slightly beyond the side of the car, and has a suitable rest provided for it.

G is a chamber formed in rear of and above 90 the chamber *A'*, into which the ball holding the link in place is thrown, as shown in Fig. 2, either by the action of the arm *E*, when it is desired to release the link and the spindle *D* is turned either from the top or side of the 95 car, or by the entrance of the link *B* itself. The shape of this recess *G* insures the return of the ball to its normal position—*i. e.*, that shown in Figs. 1 and 5—and the consequent 100 retention of the link in the chamber *A'*.

H is a hole through which, if desired, the ordinary pin may be put. Its lower end will pass through the slot A³.

Having thus described my invention, I beg 5 to state that what I claim is as follows:

1. A car-coupler having an oval internal chamber, in which is contained a ball dropping automatically into place on the entry of the link, so as to hold it in position, substantially as specified.

2. The combination, with the chamber A' and ball C, contained therein, and adapted to

lodge in and retain the link, of recess G, as and for the purposes set forth.

3. The combination, with the ball C, contained in chamber A', provided with recess G, of arm E, mounted on pivot-spindle D, all constructed and operating substantially as and for the purposes set forth.

Montreal, 24th day of November, A. D. 1881.

GEORGE O. S. CONWAY.
